(57) **CLAIM**

I claim the ornamental design for a water-fillable human body simulator, as shown and described.

DESCRIPTION

FIG. 1 is an isometric view of a water-fillable human body simulator.

FIG. 2 is a rear elevation view of the water-fillable human body simulator of FIG. 1.

FIG. 3 is a front elevation view of the water-fillable human body simulator of FIG. 1.

FIG. 4 is a left side elevation view of the water-fillable human body simulator of FIG. 1. A right side elevation view is a mirror image of the left side elevation view.

FIG. 5 is a top plan view of the water-fillable human body simulator of FIG. 1.

FIG. 6 is a bottom plan view of the water-fillable human body simulator of FIG. 1; and,

FIG. 7 is an isometric view of the water-fillable human body simulator of FIG. 1 deployed in a rescue stretcher.

In FIGS. 1 and 3-7, the dashed lines showing a representation of facial features, nozzles, and caps are for illustrative purposes only and form no part of the claimed design.

In FIG. 7, the dashed lines showing the rescue stretcher illustrate environment of use only and form no part of the claimed design.

The broken lines depict environment and portions of the article that form no part of the claimed design.
